WINDER DRIVE

Ransom Tyler, Greenfield, Wis., assignor to The
Oilgear Company, Milwaukee, Wis., a corpora-
tion of Wisconsin

Application October 16, 1944, Serial No. 558,843

7 Claims. (Cl. 242—75)

1

This invention relates to hydraulic drives and more particularly to a drive of the type employed to drive a winding machine which winds sheet or strip material into a roll as fast as it is delivered thereto from a mill or other machine.

Winder drives now in use maintain tension upon the sheet or strip during the winding operation and some of them are capable of maintaining the tension within reasonable limits after the mill and the winder have been brought up to running speed but during acceleration and deceleration the tension varies through a wide range. A substantial variation in the tension exerted upon a thin metal strip or metal foil is very objectionable as it tends to cause a variation in the gage of the metal.

One object of the invention is to provide a winder drive which will exert tension upon the sheet or strip before the winding operation begins and will maintain a substantially uniform tension upon the sheet or strip during the winding operation.

Another object is to provide a winder drive which will exert tension upon the sheet or strip and will maintain the tension within closer limits than was heretofore possible during acceleration and deceleration of the sheet or strip.

Other objects and advantages of the invention will appear from the following description of an embodiment of the invention which is shown schematically in the accompanying drawing.

For the purpose of illustration, the drive has been shown as being employed to drive a winding machine which is adapted to wind sheet material into a roll as fast as it issues from a mill or other machine. Since neither machine forms any part of the present invention, the winding machine has been represented by a winding shaft 1 on which the sheet is to be wound and the mill has been represented by a pair of delivery rolls 2—2 between which the sheet passes.

The drive includes a variable displacement hydraulic motor 3, which is adapted to drive winding shaft 1 through a suitable driving connection 4, and a pump 5 which is driven from delivery rolls 2 through a suitable driving connection 6. Motor 3 and pump 5 are hydraulically connected to each other by two channels 7 and 8 which form therewith a closed hydraulic circuit, channel 7 having arranged therein a check valve 9 which permits liquid to flow freely from the outlet of pump 5 to the inlet of motor 3 but prevents liquid from entering the outlet of pump 5. Channels 7 and 8 may be connected to each

2

other through a normally closed manually operable valve 10.

The drive also includes an auxiliary pump 15 which is continuously driven by an electric motor 16. Pump 15 draws liquid from a reservoir 11 and discharges it into a branched supply channel 18 one branch of which is connected to channel 7 to enable pump 15 to make up leakage losses in the main hydraulic circuit and to maintain pressure in channel 7 during the winding operation at which time a part of the liquid discharged by pump 15 is employed to energize a small hydraulic motor 19 which drives a flywheel 20 and has a branch of channel 18 connected to its inlet. The outlet of motor 19 is connected to the inlet of a tension control resistance valve 21 the outlet of which is connected by a channel 22 to reservoir 17 and to the intake of pump 15.

When the drive is idle, pump 15 is bypassed through a valve 23 having a piston 24 fitted in its casing 25 and normally held in a bypass position by a spring 26. A branch of channel 18 is connected to casing 25 adjacent the normal position of piston 24 and both ends of casing 25 are connected by a channel 27 to return channel 22. The arrangement is such that, when valve 23 is open, all the liquid discharged by pump 15 flows through channel 18, valve 23, channel 27 and channel 22 to the intake of pump 15 and, when valve 23 is closed, the liquid discharged by pump 15 is directed to channel 7 and to motor 19.

Valve 23 may be operated manually or in any suitable manner but it is ordinarily closed by a solenoid 28 the armature of which is connected to the stem of piston 24. Solenoid 28 is controlled by a switch such as a push button switch 29 arranged in a control panel 30.

When valve 23 is closed, the pressure that can be created by pump 15 is limited by a safety valve 31 which in practice is built into pump 15 but which for the purpose of illustration has been shown connected between channel 18 and reservoir 17.

Hydraulic motor 3 has a displacement varying member or slide block 35 which is shiftable toward and from a minimum displacement position to vary the speed of motor 3 relative to the rate at which motive liquid is delivered thereto. Slide block 35 is adapted to be moved toward its maximum displacement position by a servo-motor having a piston 36 fitted in a stationary cylinder 37 carried by the pump casing on one side thereof, and it is adapted to be moved toward its minimum displacement position by a servo-motor having a piston 38 fitted in a stationary cylinder 39 car-

ried by the plump casing on the other side thereof. The maximum displacement position of slide block 35 is determined by an adjusting screw 40 threaded through the head of cylinder 39 to engage piston 38 and its minimum displacement position is determined by an adjusting screw 41 threaded through the head of cylinder 37 to engage the head of piston 36.

Servo-motor 36-37 is energized by liquid supplied to cylinder 37 through a channel 42 from a gear pump 43 which is ordinarily driven in unison with pump 15 and arranged in the casing thereof according to the usual practice but which for the purpose of illustration has been shown as a separate pump and as drawing liquid from reservoir 17 and discharging it into channel 42. Liquid discharged by gear pump 43 in excess of requirements is exhausted through a relief valve 44 which enables gear pump 43 to maintain a constant pressure in cylinder 37 so that piston 36 is enabled to exert a constant force upon slide block 35.

Slide block 35 is adapted to be shifted in one direction or the other in response to a variation in the flow in channel 8 relative to the flow in channel 7. In order that this may be accomplished, cylinder 39 is connected to channel 8 by a channel 45 and channel 8 is connected to reservoir 17 by a channel 46 having arranged therein a resistance valve 47 which, if pistons 36 and 38 have the same effective pressure areas, will open at a pressure somewhat higher than gear pump pressure.

The arrangement is such that, when motor 3 discharges more liquid into channel 8 than can enter pump 5, the excess liquid will flow through channel 45 to cylinder 39 and cause piston 38 to move slide block 35 in a direction to decrease the displacement of motor 3. Piston 36 will move with slide block 35 and eject liquid from cylinder 37 through channel 42 and relief valve 44 into reservoir 17. After piston 36 engages adjusting screw 41 and stops further movement of slide block 35, any liquid discharged by motor 3 in excess of the liquid that can enter pump 5 is exhausted through resistance valve 47 and channel 46 into reservoir 17. When pump 5 attempts to draw more liquid from channel 8 than is discharged into it by motor 3, the pressure in channel 8 and in cylinder 39 will drop and permit the gear pump liquid to move piston 36 and slide block 35 in a direction to increase the displacement of motor 3.

If desired, means may be provided for causing the mill or other machine to start immediately after the end of the sheet has been attached to winding shaft 1 and the slack has been pulled out of the sheet. For example, the mill or other machine may be caused to start in response to the closing of a switch 50 which closes in response to the creation of a predetermined pressure in channel 7. As shown, switch 50 is adapted to be closed by a piston 51 fitted in a stationary cylinder 52 which is connected to channel 7 by a channel 53. Piston 51 is urged to its inoperative position by a spring 54 the tension of which may be adjusted by a nut 55 to a value great enough to prevent piston 51 from closing switch 50 until the sheet becomes taut.

Operation

Assuming that the parts are in the positions shown, that pump 15 is running, that the mill is idle and that enough of the sheet extends beyond rolls 2 to permit the end thereof to be

fastened to a suitable core fixed on winding shaft 1, the drive will operate as follows:

Motor 3 will be idle for the reason that pump 5 is idle and pump 15 is being bypassed through valve 23. The operator will first attach the end of the sheet to winding shaft 1 with as little slack in the sheet as possible and then he will close bypass valve 23 if it is manually operable or he will close a switch, such as switch 29, to cause valve 23 to close if it is electrically controlled.

With valve 23 closed, the liquid discharged by pump 15 must flow either through channel 18 to motor 19 or through channels 18 and 7 to motor 3 since check valve 8 prevents the liquid from entering pump 5. The inertia of flywheel 20 resists rotation of motor 19 and tension control valve 21 resists the discharge of liquid from motor 19 which causes pump 15 to create sufficient pressure to enable the liquid to start motor 3 which will rotate winding shaft 1 to pull the sheet taut and exert tension thereon.

Since there is only a little slack in the sheet, motor 3 needs to rotate but little to pull the slack out of the sheet. As soon as motor 3 starts to rotate, it discharges liquid into channel 8 and, since pump 5 is idle at this time so that the liquid cannot enter it, the liquid flows through channel 45 to cylinder 39 and causes piston 38 to reduce the displacement of motor 3. However, the pressure required to start and accelerate motor 19 is great enough to enable motor 3 to start the winding machine and cause it to exert tension upon the sheet even when motor 3 is at its minimum displacement as determined by the adjustment of screw 41. When a predetermined tension is exerted upon the sheet, motor 3 will stop and maintain that tension unless the mill is started the instant that the sheet becomes taut.

Operators of winding machines are ordinarily highly skilled and able to operate the mill starting mechanism just as or just before the sheet becomes taut but, if desired, the mill may be started automatically in any suitable manner such as by means of switch 50. If switch 50 is employed, motor 3 will stop when the sheet becomes taut and then all of the liquid discharged by pump 15 will tend to flow through motor 19 but, since flywheel 20 can not be accelerated to full speed instantly, pump 15 must increase the pressure until it is high enough to open safety valve 31 and then the excess liquid will flow therethrough to reservoir 17. The increased pressure will extend through channels 18, 7 and 53 to cylinder 52 and cause piston 51 to close switch 50 and thereby cause the mill to start.

Starting the mill either manually or automatically causes rolls 2 to deliver the sheet to shaft 1 and to drive pump 5 which will discharge liquid into channel 7 and draw liquid from channel 8 at a rate proportional to the rate at which the sheet is delivered to shaft 1.

The liquid discharged into channel 7 by pumps 5 and 15 will energize motor 3 which will rotate shaft 1 to wind the sheet thereon and to maintain tension on the sheet. Motor 3 ordinarily has sufficient torque at its minimum displacement to start shaft 1 and to accelerate it as fast as the sheet is delivered thereto but if for any reason it did not have sufficient torque to do so it would not discharge liquid into channel 8 as fast as pump 5 drew liquid therefrom which would cause the pressure in channel 8 to drop 75 and permit servo-motor 36-37 to increase the

displacement of motor 3 until it did have sufficient torque as previously explained.

The mill will gradually accelerate to full speed and rolls 2 will gradually increase the speed of the sheet. Pump 5 will accelerate in unison with rolls 2 and increase its rate of delivery in proportion to the increase in the speed of the sheet. This increase in delivery will accelerate motor 3 which will accelerate shaft 1 to wind the sheet thereon as fast as it is delivered thereto. Since pump 15 delivers liquid to motor 3 in addition to the liquid delivered thereto by pump 5, motor 3 tends to run faster than the rate determined by the rate at which pump 5 delivers liquid thereto which rate is proportional to the speed of the sheet. Consequently, motor 3 maintains tension upon the sheet.

The parts are so proportioned that flywheel 20 reaches full speed at approximately the same time that the mill reaches full speed. Thereafter, all of the liquid discharged by pump 15 passes through motor 19 and tension control valve 21 except a small portion required to make up for leakage losses and to maintain pressure in channel 1 so that the pressure in channel 1 is determined by the resistance of valve 21. The tension exerted upon the sheet is dependent upon the torque of motor 3 which is dependent upon the pressure in channel 1. Therefore, the tension is determined by valve 21 which may be adjusted to vary the tension.

As the sheet accumulates upon shaft 1, the peripheral speed of the roll of sheet material on shaft 1 will remain the same as the linear speed of the sheet but the rotary speed of shaft 1 will decrease due to the increase in the diameter of the roll of sheet material. Decreasing the speed of shaft 1 causes motor 3 to slow down and tend to deliver less liquid into channel 8 than is drawn therefrom by pump 5 so that the pressure in channel 8 and in cylinder 39 drops and permits servo-motor 36-37 to increase the displacement of motor 3 and thereby increase the rate of motor discharge relative to the rate of motor speed so that the pressure in channel 8 and in cylinder 39 is prevented from decreasing. The gradual increase in the diameter of the roll of material on shaft 1 thus causes motor 3 to gradually increase its displacement and its torque so that it maintains a constant tension on the sheet during the winding operation.

The winder drive described herein is susceptible of various modifications and adaptations without departing from the scope of the invention which is hereby claimed as follows:

1. In a mechanism having rolls for delivering strip material and a winder roll for winding said strip material thereon as fast as it is delivered by said rolls, the combination of a variable displacement hydraulic motor connected to said winder roll to drive the same, a main pump driven in unison with said delivery rolls for delivering motive liquid to said motor to energize the same, fluid channels connecting said pump and said motor and forming therewith a hydraulic circuit having pressure and return sides, a relatively small pump driven independently of said main pump and connected to the pressure side of said circuit to supply additional liquid thereto and thereby enable said motor to exert tension upon said strip material when said delivery rolls and said main pump are idle, and a bypass for the escape of liquid discharged by said small pump in excess of the liquid required by said motor, said bypass including means pro-

viding a gradually decreasing resistance to the flow through said bypass to thereby enable said small pump to create a pressure which is initially maximum and decreases to a predetermined minimum during continued flow through said bypass.

2. In a mechanism having rolls for delivering strip material and a winder roll for winding said strip material thereon as fast as it is delivered by said rolls, the combination of a variable displacement hydraulic motor connected to said winder roll to drive the same, a main pump driven in unison with said delivery rolls for delivering motive liquid to said motor to energize the same, fluid channels connecting said pump and said motor and forming therewith a hydraulic circuit having pressure and return sides, a relatively small pump driven independently of said main pump and connected to the pressure side of said circuit to supply additional liquid thereto and thereby enable said motor to exert tension upon said strip material when said delivery rolls and said main pump are idle, and a bypass for the escape of liquid discharged by said small pump in excess of the liquid required by said motor, said bypass including a substantially constant resistance and means which provides a gradually decreasing resistance to the flow of liquid through said bypass and which coacts with said constant resistance to enable said small pump to create a pressure which is initially maximum and gradually decreases to a predetermined minimum during continued flow through said bypass.

3. In a mechanism having rolls for delivering strip material and a winder roll for winding said strip material thereon as fast as it is delivered by said rolls, the combination of a variable displacement hydraulic motor connected to said winder roll to drive the same, a main pump driven in unison with said delivery rolls for delivering motive liquid to said motor to energize the same, fluid channels connecting said pump and said motor and forming therewith a hydraulic circuit having pressure and return sides, a relatively small pump driven independently of said main pump and connected to the pressure side of said circuit to supply additional liquid thereto and thereby enable said motor to exert tension upon said strip material when said delivery rolls and said main pump are idle, a bypass for the escape of liquid discharged by said small pump in excess of the liquid required by said motor, said bypass including a substantially constant resistance and means which provides a gradually decreasing resistance to the flow of liquid through said bypass and which coacts with said constant resistance to enable said small pump to create a pressure which is initially maximum and gradually decreases to a predetermined minimum during continued flow through said bypass means responsive to an increase in pressure in the return side of said circuit for reducing the displacement of said motor, and a relief valve providing escape of liquid from the return side of said circuit in response to the pressure therein reaching a given maximum.

4. In a mechanism having rolls for delivering strip material and a winder roll for winding said strip material thereon as fast as it is delivered by said rolls, the combination of a variable displacement hydraulic motor connected to said winder roll to drive the same, a main pump driven in unison with said delivery rolls for delivering motive liquid to said motor to energize

the same, fluid channels connecting said pump and said motor and forming therewith a hydraulic circuit having pressure and return sides, an auxiliary motor, a flywheel driven by said auxiliary motor, an independently driven auxiliary pump connected to said auxiliary motor and to the pressure side of said circuit, a tension control valve connected in series with said auxiliary motor to resist the flow of liquid therethrough, and a valve adapted when open to bypass said auxiliary pump and adapted when closed to cause the liquid discharged by said auxiliary pump to tend to start said auxiliary motor and to create pressure in the pressure side of said circuit to thereby enable said variable displacement motor to start before said main pump starts.

5. In a mechanism having rolls for delivering strip material and a winder roll for winding said strip material thereon as fast as it is delivered by said rolls, the combination of a variable displacement hydraulic motor connected to said winder roll to drive the same, a main pump driven in unison with said delivery rolls for delivering motive liquid to said motor to energize the same, fluid channels connecting said pump and said motor and forming therewith a hydraulic circuit having pressure and return sides, an auxiliary motor, a flywheel driven by said auxiliary motor, an independently driven auxiliary pump connected to said auxiliary motor and to the pressure side of said circuit, a tension control valve connected in series with said auxiliary motor to resist the flow of liquid therethrough, a valve adapted when open to bypass said auxiliary pump and adapted when closed to cause the liquid discharged by said auxiliary pump to tend to start said auxiliary motor and to create pressure in the pressure side of said circuit to thereby enable said variable displacement motor to start before said main pump starts, and a check valve arranged in the pressure side of said circuit adjacent said main pump to prevent liquid delivered by said auxiliary pump from entering said main pump.

6. In a mechanism having rolls for delivering strip material and a winder roll for winding said strip material thereon as fast as it is delivered by said rolls, the combination of a variable displacement hydraulic motor connected to said winder roll to drive the same, a main pump

8
driven in unison with said delivery rolls for delivering motive liquid to said motor to energize the same, fluid channels connecting said pump and said motor and forming therewith a hydraulic circuit having pressure and return sides, an auxiliary motor, a flywheel driven by said auxiliary motor, an independently driven auxiliary pump connected to said auxiliary motor and to the pressure side of said circuit, a tension control valve connected in series with said auxiliary motor to resist the flow of liquid therethrough, a valve adapted when open to bypass said auxiliary pump and adapted when closed to cause the liquid discharged by said auxiliary pump to tend to start said auxiliary motor and to create pressure in the pressure side of said circuit to thereby enable said variable displacement motor to start before said main pump starts, and means responsive to a variation in the pressure in the return side of said circuit for varying the displacement of said motor.
